PHONOGRAPH

Melvin H. Boldt, Glenview, Ill., assignor to Rowe
International, Inc., Whipppany, N.J.

Filed June 21, 1973, Ser. No. 372,081

Term of patent 14 years

Int. Cl. D14—01

U.S. Cl. D56—4 R

FIG. 1 is a front elevational view of a phonograph showing my new design in which the pattern indicated by hatching in two of the rectangular areas is continuous within the rectangles;

FIG. 2 is a right side elevational view;

FIG. 3 is a left side elevational view;

FIG. 4 is a top plan view; and

FIG. 5 is a rear elevational view, drawn on a reduced scale.

I claim:

The ornamental design for a phonograph, substantially as shown and described.
